Primary Examiner — Kevin K Rudzinski

(57) **CLAIM**

The ornamental design for a zipper tooth, as shown and described.

DESCRIPTION

FIG. 1 is a top, front and right side perspective view of a first embodiment of a zipper tooth showing our new design; FIG. 2 is a bottom, rear and left side perspective view of FIG. 1;

FIG. 3 is a front elevational view of FIG. 1; FIG. 4 is a rear elevational view of FIG. 1; FIG. 5 is a left side view of FIG. 1; FIG. 6 is a right side view of FIG. 1; FIG. 7 is a top plan view of FIG. 1; FIG. 8 is a bottom plan view of FIG. 1; FIG. 9 is a top, front and right side perspective view of a second embodiment of the zipper tooth; FIG. 10 is a bottom, rear and left side perspective view of FIG. 9; FIG. 11 is a front elevational view of FIG. 9; FIG. 12 is a rear elevational view of FIG. 9; FIG. 13 is a left side view of FIG. 9; FIG. 14 is a right side view of FIG. 9; FIG. 15 is a top plan view of FIG. 9; FIG. 16 is a bottom plan view of FIG. 9; FIG. 17 is a top, front and right side perspective view of a third embodiment of the zipper tooth; FIG. 18 is a bottom, rear and left side perspective view of FIG. 17; FIG. 19 is a front elevational view of FIG. 17; FIG. 20 is a rear elevational view of FIG. 17;

(Continued)

FIG. 21 is a left side view of FIG. 17;
 FIG. 22 is a right side view of FIG. 17;
 FIG. 23 is a top plan view of FIG. 17;
 FIG. 24 is a bottom plan view of FIG. 17;
 FIG. 25 is a top perspective view showing the zipper tooth of FIG. 17 in a use state;
 FIG. 26 is a bottom perspective view showing the zipper tooth of FIG. 17 in a use state;
 FIG. 27 is a top, front and right side perspective view of a fourth embodiment of the zipper tooth;
 FIG. 28 is a bottom, rear and left side perspective view of FIG. 27;
 FIG. 29 is a front elevational view of FIG. 27;
 FIG. 30 is a rear elevational view of FIG. 27;
 FIG. 31 is a left side view of FIG. 27;
 FIG. 32 is a right side view of FIG. 27;
 FIG. 33 is a top plan view of FIG. 27;
 FIG. 34 is a bottom plan view of FIG. 27;
 FIG. 35 is a top perspective view showing the zipper tooth of FIG. 27 in a use state; and,
 FIG. 36 is a bottom perspective view showing the zipper tooth of FIG. 27 in a use state.
 The broken lines in FIGS. 25-26 and 35-36 depict environment and are for illustrative purposes only and form no part of the claimed design.

1 Claim, 36 Drawing Sheets
